UNITED STATES PATENT OFFICE.

THEODOR BECHER, OF GUSTAVSBURG, GERMANY, ASSIGNOR TO MASCHINENFABRIK AUGSBURG-NUERNBERG, A. G., OF NUERNBERG, BAVARIA, GERMANY, A CORPORATION OF GERMANY.

SEGMENT GATE.

1,422,076.

Specification of Letters Patent. Patented July 11, 1922.

Application filed April 11, 1922. Serial No. 551,740.

To all whom it may concern:

Be it known that I, THEODOR BECHER, a citizen of Germany, residing at Gustavsburg, Germany, have invented certain new 5 and useful Improvements in Segment Gates (for which I have filed application in Germany April 28, 1920), of which the following is a specification.

My invention relates to well known segment gates consisting of two parts of which the upper segment leaf lies behind the lower and can be lowered under the upper edge of the upper retaining plate, but a constructional drawback lies in the fact 10 that the supporting arms of both segment leaves which swing around the same pivot have to cross each other at the lowering of the upper segment leaf which causes difficulties, especially in case of large segments 15 and segments of broad span, because it is not easy to give the open frame of the bracings a sufficient carrying capacity.

It is possible to avoid this difficulty by adopting the way which has already been 20 suggested for old and small segments viz. that the supporting arms are placed beside each other and thus a crossing of each other is no longer necessary. This arrangement has, however, the great disadvantage that 25 the two supporting arms owing to their breadth and position can no longer be placed in the cavity of the lateral masonry or pier and therefore the arms are subject to damage through ice or floating materials of 30 any kind. Another way would be to deepen the lateral cavities accordingly, but this 35 would require a considerable increase of

the breadth and thus increase immensely the costs of the masonry.

Following the invention these difficulties 40 are avoided in such a manner that the upper segment leaf is journalled to swing on a special pivot arranged on the supporting arm of the lower segment.

The drawing shows such a segment gate 45 in cross section. The lower segment leaf *a* is supported through its bracings *b* against the bearing *c* and can swing around the pivot *d*. The upper segment leaf *e* turns around the supporting arm *f* and the pivot 50 *g* which is arranged on the lower segment leaf. As may easily be seen from the drawing the arrangement of the bracings of both segments do not interfere with each other therefore the bearing *c* as well as the bracings *b* of the lower segment can be made 55 considerably simpler as under the usual arrangement. The slight difference of the curve radius of the upper and lower segment is of no importance to the operation 60 and construction of the gate.

What I claim is:

A segment gate consisting of two parts being arranged one above the other in such a manner that the upper segment leaf is 65 journalled to swing on a special pivot arranged on the supporting arm of the lower segment leaf.

In testimony whereof I affix my signature in presence of two witnesses.

THEODOR BECHER.
